UNITED STATES PATENT OFFICE.

LEWIS KALLING, OF BALTIMORE, MARYLAND.

BOTTLE-SEALING CAP.

No. 882,889.

Specification of Letters Patent. Patented March 24, 1908.

Application filed August 6, 1907. Serial No. 387,285.

To all whom it may concern:

Be it known that I, LEWIS KALLING, of the city of Baltimore and State of Maryland, have invented certain Improvements in Bottle-Sealing Caps, of which the following is a specification.

This invention relates to certain improvements in a bottle sealing cap which embodies as essential features thereof, a crown having 10 a pendent flange the lower edge of which is adapted to be turned in and under a shoulder generally produced in bottles by the projection of the head beyond the neck, to hold the crown in contact with the lip of the bottle, 15 and a joint-forming ring or disk which is enclosed by the pendent flange and in contact with the crown.

The said invention consists in a peculiar formation of the flange of the sealing cap, as 20 will hereinafter fully appear.

In the further description of the said invention which follows, reference is made to the accompanying drawing forming a part hereof, and in which,—

25 Figure 1 is a central vertical section of a bottle head provided with the improved sealing cap, the cap being shown as it would appear before the sealing operation. Fig. 2 shows the bottle head and sealing cap after 30 the sealing operation. Fig. 3 is a partly broken edge view of the sealing cap alone the same being enlarged to more fully illustrate the nature of the corrugations at its edge. Fig. 4 illustrates the sealing cap provided 35 with a joint-forming disk instead of a ring as shown in Figs. 1 and 2.

Referring now to Figs. 1, 2 and 3 of the drawing, 1 represents a bottle head having the shoulder *a*. The bottle cap which is 40 preferably formed of tin plate, consists of the crown 2, the pendent annular flange 3 and the compressible joint-forming ring 4.

To fully understand the nature of the present invention it must be borne in mind 45 that in drawing or stamping a bottle seal or any cap-shaped device from a flat disk, the portion of the material which may be termed the flange, owing to its reduction from the original diameter must necessarily 50 be lengthened or thickened or crimped, and in any case the material is stiffened. Again, if the extreme edge of the flange is turned inward, the renewed reduction in diameter

causes a further concentration of the material and an additional increase in rigidity. 55

As in the present invention hereinafter fully described, the edge of the flange is turned in and consequently reduced in diameter, and has to be further reduced in diameter in the application of the cap to a 60 bottle head, the object of the said invention is to facilitate the last named reduction in diameter, or make it possible to reduce the diameter of the inturned edge of the flange without materially disturbing the molecular 65 condition of the metal.

My invention therefore consists in corrugating or crimping the inturned edge of the flange, which corrugation *b*, as the said edge is reduced in diameter in the application 70 of the sealing cap to the bottle head, is merely accentuated, the crimps being deepened and slightly closed. By this construction of the flange of the sealing cap, less pressure is required to apply the cap to the 75 bottle head, and less force necessary to remove the cap from the bottle; while reflection of the compressed portion of the cap upon the withdrawal of the capping tool if not entirely obviated, is materially reduced.

In Fig. 4 a compressible disk 4^a is shown as substituted for the joint-forming ring 4.

The capping operation consists in changing the sealing cap from the form shown in 85 Fig. 1 to that illustrated in Fig. 2 in which the corrugated edge of the cap is brought tightly in contact with the bottle at a point slightly below the shoulder *a* of the bottle 90 head.

I claim as my invention:

1. In combination with a bottle head, a sealing cap for the same which comprises a crown, a pendent annular flange and a joint-forming device, the edge of the said flange 95 being turned inward and corrugated, substantially as specified.

2. A sealing cap for a bottle which consists of a crown having a downwardly extending annular flange the edge of which is 100 turned inward and corrugated, substantially as specified.

LEWIS KALLING.
